UNITED STATES PATENT OFFICE.

JOHN J. A. MILLER, OF DENVER, COLORADO.

METAL CLIP FOR BINDING ROPE ENDS AND FOR USE IN ROPE-SPlicing.

1,114,791.

Specification of Letters Patent.

Patented Oct. 27, 1914.

Application filed November 17, 1913. Serial No. 801,515.

To all whom it may concern:

Be it known that I, JOHN J. A. MILLER, a citizen of the United States of America, residing in the city and county of Denver 5 and State of Colorado, have invented a new and useful Metal Clip for Binding Rope Ends and for Use in Rope-Splicing, of which the following is a specification.

My invention relates to an improved 10 metal clip for use in rope splicing and also for securing the loose strands of hemp and wire rope ends together, and the objects of my invention are: First. To provide a metal clip for binding the loose strands of rope 15 ends and for binding the strands in rope splicing, said clips being adapted to encircle and extend through and clamp the layers of the rope together. Second. To provide a rope splice binding and rope end binding 20 clip that can be quickly and easily applied to splicings and in binding the strands of rope ends. I attain these objects by the mechanism illustrated and described in the accompanying drawings, in which,

25 Figure 1 is a view of a piece of ordinary hemp rope, showing the strands thereof bound together adjacent to one end by the improved clip. Fig. 2 is a similar view of the opposite side of the rope, showing the manner of securing the ends or points of 30 the clip prongs to the said rope. Fig. 3 is a sectional view on the line 3—3 of Fig. 1. Fig. 4 is a plan view of one of the clips before the same has been bent, the clip being 35 stamped from sheet metal. Fig. 5 is a perspective view of the clip showing the prongs thereof partially bent for convenience of attachment to the rope. Fig. 6 is a front view showing the clip bent into the position it 40 occupies when clamped upon a rope. Fig. 7 is a plan view of a clip, the prongs of which are circular in cross section. And Fig. 8 is a view showing the application of the clip in splicing rope.

45 Similar letters of reference refer to similar parts throughout the several views.

Referring to the drawings, the numeral 1 50 designates the rope encircling or band portion of a clip embodying my invention, the ends of which terminate in pointed prongs 2 and 3. The prongs 2 and 3 are each straight on one edge and inclined on the other edge, so that when the clip is bent into circular form the inclined edges rest one 55 against the other, as shown in Fig. 2, thus maintaining a uniform width of band. The

clips are made of different lengths for different sizes of ropes, the full length of a clip for a given size rope being sufficient to permit the clip to be wrapped around the 60 rope, its ends overlapping or passing each other side by side, enough to allow one prong to extend to the center of one strand of the rope, and the opposite prong to extend past it to the next strand of the rope, 65 and the prongs are each bent substantially at right angles to the body of the band and in the same direction, and after the clip is bent around the rope these angular bent ends are driven into the strands of the rope. 70 From the center of the band 1 and at right angles thereto, projects an integral prong 4, which is preferably bent in the manner shown in Fig. 5 for convenience in attaching the clip to the rope. This prong is made 75 long enough to extend entirely through and beyond the surface of the rope when the clip is placed thereon, so that it may be bent to lap over onto one or both of the prongs 2 and 3 when the clips are clamped upon the 80 rope. The clip thus comprises a band, the ends of which are in the form of prongs, and a prong extending at right angles to the band, the improved clip being designed 85 to be used for binding the loose strands of rope ends and thus take the place of the usual wrapping which is employed for preventing the strands from becoming un-twisted.

The band 1 of the clip is clamped upon 90 the rope with sufficient force to embed it slightly into the surface of the rope, so that it will not form an obstruction in handling or in operation when passing over a sheave wheel. In order that the point of the prong 95 4, which overlaps one of the prongs 2 or 3, may not project beyond the surface of the rope and thus form an obstruction, an indentation 5 may be formed in one or both of the prongs 2 and 3, near their pointed 100 ends, which will receive the pointed end of the prong 4, and thus permit it to lie flush with the surface of the ropes, as will be fully understood by reference to the accompanying drawings.

105 The clip shown in Figs. 1 to 6 inclusive, may be stamped from sheet metal of suitable character, but in Fig. 7 is illustrated a clip 6, the prongs of which are round in cross section. In other respects, the clip 110 6 is identical with that shown in the other figures.

In Fig. 8 is illustrated a view illustrating the application of the clip in rope splicing. In splicing the ends of a rope together in the usual way, the strands of each of the ends are untwisted for a suitable length, and the untwisted portions are placed together, crotch to crotch, and a strand from one end is tied with a strand from the other end to form a knot 7, the letter B indicating where the two crotches unite, the rope illustrated being a three strand rope. Then a strand 8 of one rope end X is untwisted for a suitable distance, and a strand 9 from the other rope end Y is wound or twisted into the space previously occupied by the strand 8, and the strands 8 and 9 are then formed into a knot 10 at the point A. In the same manner, the remaining strand 11 of the rope end Y is untwisted for a suitable distance, and the remaining strand 12 of the rope end X is twisted into the space previously occupied by the strand 11, and the strands 11 and 12 are tied to form a knot 13 at the point C. In the usual manner of splicing, the tied ends at A, B and C would be secured by tucking them under other strands of the ropes, a process which is not only difficult, but requires considerable skill, especially in cases of wire rope splicing, and it is to eliminate this difficult feature that my improved clip is employed. At the points 7, 10 and 13, where the knots occur, the improved clips are secured in the manner before described, the clips being shown only at B and C, and being omitted at A, so that the knot may be clearly seen. These clips prevent the knots from becoming untied, and untwisting of the strands is prevented by securing a clip on each side of the knot-securing clip, as shown at the points B and C. After the clips have been secured, the ends from which the knots are tied, are cut

off close to the rope, as at the point C. Thus the improved clip not only lessens the time and labor required in splicing rope, but it enables a much stronger and neater splice to be made, and when they have become worn or broken they can be easily removed and replaced with new clips. 45

Having described my invention, what I claim as new and desire to secure by Letters Patent, is:

1. A clip for the purpose specified, comprising a metal strip, the opposite edges of which are cut off at an inclination to form with the straight edge a pointed prong, one of said prongs having a transverse indentation, and a pointed prong extending at right angles from said strip, said strip being adapted to be bent to encircle a rope, its 55 pointed ends passing each other and bent at an angle and embedded in the said rope, and the right angled prong extending through the rope, its pointed end being bent and resting in the said indentation. 65

2. The combination with a rope, of a strand binding clip therefor, comprising a pliable metal strip, the opposite edges of which are cut off at an inclination to form pointed prongs, said strip being bent to encircle the rope, its inclined edges adjoining and its pointed ends passing each other, and being bent at an angle and embedded in the rope, and a pointed prong extending at right angles to the strip, said prong being 70 passed through the rope, its pointed end being bent to overlap one of the prongs of the strip. 75

In testimony whereof I affix my signature in presence of two witnesses.

JOHN J. A. MILLER.
